UNITED STATES PATENT OFFICE.

ROCHUS MAX zu LYNAR PASSY-DE CHIMANG, OF NEW YORK, N. Y., ASSIGNOR TO MAR-DE-PASSY CORPORATION, OF NEW YORK, N. Y., A CORPORATION OF NEW YORK.

MARINE VESSEL AND SHIP.

Refiled for abandoned application Serial No. 524,478, filed December 23, 1921. This application filed December 19, 1925. Serial No. 76,562.

My invention relates to marine vessels, more particularly to new and useful improvements in the construction of the hulls of marine vessels.

5 The principal objects of my invention are: (1) The provision of a hull embodying such novel features of construction as will involve a marked diminution of the resisting forces opposing the progress of the vessel 10 through the water, and thereby to enable a substantial increase in speed; (2) the provision of a hull of this character having improved features of stability, designed to moderate undesirable angular oscillation, 15 whether about a horizontal longitudinal axis or about a horizontal transverse axis; and (3) the provision of a hull of this character, with which the propeller and rudder are associated in such manner that while sheltered 20 from surface and wave disturbances, they can receive, nevertheless, a free and solid flow of water for their efficient operation, these parts being arranged so that they will be wholly submerged under all conditions of 25 lading and in all kinds of weather.

With the foregoing objects in view and others, the invention resides in the combination, arrangement, and construction of parts hereinafter described, defined in the appended claims, and illustrated in the accompanying drawings, forming a material part of this specification; and it will be understood that changes and alterations in the precise embodiment of the invention as herein disclosed, may be made, to which changes and alterations the inventor is entitled, provided the same are effected within the scope of what is claimed.

40 The preferred embodiment of my invention, as reduced to practice, is illustrated in the accompanying drawings, in which:—

Fig. 1 is a view in side elevation of a vessel constructed in accordance with my invention; Fig. 2 is an underneath bottom 45 plan view thereof. Figs. 3 to 14 represent a series of partial cross-sectional views, taken on Fig. 1, each view being taken on a line thereof, which is indicated by a numeral of reference corresponding to the numeral of 50 its respective figure; thus, Fig. 3 is taken on a line 3—3 of Fig. 1; Fig. 4 on the line 4—4 thereof; Fig. 5 on the line 5—5; and so on throughout the series.

Some of the academic considerations with

which I have been concerned in working out the details of construction of my improved hull are the following:—That the form of the hull structure and the manner in which it plows through and rides upon the water have much to do with the rapid movement 55 of the vessel; that the series of wave-impulses of the sea and the many wakes and eddies resulting partly therefrom and partly from the form of the hull and its underwater fittings constitute serious obstacles to 60 the rapid progress of the vessel; and that the extension laterally with respect to the greatest possible distance of the center of gravity, of concentrating "weights," bilges and keels has an important bearing in reference to controlling the rolling and pitching 65 oscillations of the vessel, and more particularly when considered in relation to the contour and lines of continuity of the hull, and in relation as well to the location of the propeller and rudder. Those skilled in the art 70 will, of course, readily understand that by the term "weights" I mean the relation which the body parts, extensions, keels, load and the like bear to both the longitudinal and 75 transverse axes.

Having these principles in mind, my improved hull is designed to cleave the water with the least possible resistance and to float its greatest breadth of beam, which occurs 80 in the forebody, upon a substantially flat bottom; then by "weights," bilges and keels to stabilize the vessel, employing as means 85 conducive to that end a pair of longitudinal water channels which unite aft of the longitudinal center to form a single channel defined by uniformly diverging bilges and keels and a uniformly flattening hull bottom; and then finally to have the single 90 channel open in an area spread wider than 95 the rounded stern. In this construction also, an essential feature is the location of the propeller and the rudder underneath the hull aft of its longitudinal center and at the confluence of the two channels with the 100 single one.

In the accompanying drawings, the hull of the vessel, denoted as an entity by the numeral 15, has its bow formed with a sharp cutwater 16, the sides 17 of the bow, more 105 particularly the freeboard region thereof, expanding hurriedly but along fine lines to produce the greatest width of beam 18 in the

forebody of the vessel. From this point the sides converge along very gentle stream-lines towards the stern 19, which is gently rounded as shown.

5 With the cutwater 16 is formed at the water-line a sharp nose 20, which merges by a gentle curve with a deep main or central keel 21, the latter after a relatively short distance gently inclining upwardly to lie 10 flush with the substantially flat bottom 22, which occurs below and somewhat in advance of the greatest width of the beam.

At 23, where the substantially flat bottom region 22 merges gently into channels, as 15 will presently appear, the keel 21 recommences and gradually projects until it reaches its original depth; and then after continuing for a distance it expands laterally to produce an elliptical part 24, which 20 is hollow and has communication with the interior of the hull to accommodate the propeller shaft 25 with the fittings therefor. Carried by the shaft 25 aft of the elliptical part is a propeller screw 26; and aft of this 25 screw is a rudder 27, operatively supported by suitable brackets, secured both to the bottom of the hull and to the elliptical figure.

Adjoining the cutwater, the bottom regions 28 of the sides, below the water-line 30 bilge 29, slope rather precipitously to merge into the central keel as shown in Fig. 3. Here the sides of the hull are concaved as at 30, and the top of the hull is of considerably greater width of beam than at the 35 curves of the bilges at the water-line. Proceeding towards the stern, the bilge 29 gradually increases in size, while the precipitously sloped regions 28 gradually become horizontal, as shown in Figs. 4 and 5; the 40 bilge 29 eventually providing the commencement of an underneath bilge 31. At the same time the freeboard sides are gradually transformed as shown (Figs. 4 to 6) until there occurs the greatest width of beam at 45 the forward ends of bilges 31.

Continuing further, the flat bottom is somewhat concaved (Fig. 7); and still further the underneath bilge 31 becomes more pronounced and shows the beginning 50 of an underneath side keel 32 (Fig. 8); while the bottom at the point of the commencement of the central keel merges into two concavities, one on each side of the said central keel to provide two longitudinal 55 channels 33 and 34, as best seen in Fig. 2.

Both longitudinal sides of the hull being, of course, constructed precisely alike, both of the channels 33 and 34 are defined on their outer sides by a bilge 31 with its accompanying keel 32. As illustrated in Fig. 2, these bilge and keel structures do not extend in parallelism, but they very gradually diverge as they proceed aft, ultimately terminating as at 35 on opposite sides of the afterbody. The keels 32 attain their great-

est depth at a point approximately abreast the mid-length of the elliptical part 24, after which they gradually recede as they approach the running-out points 35, where they are of only slight depth (Figs. 8 to 13). 70 Likewise the bilges 31 as they extend aft from a point abreast the elliptical part, gradually become less pronounced.

The channels 33 and 34 unite at the aft extremity of the elliptical part, forming a 75 single channel 36, which opens between the points 35, and which spreads over an area corresponding to that of the rounded stern 19. The arches or concavities defining the channels 33 and 34 are transformed in the 80 channel 36 into a single arch or concavity, the curvature of which gradually lessens until at the stern there is almost a flat bottom 37 (Fig. 14).

In the present invention, the engine room 85 38 with its engine mechanisms is located aft of the longitudinal center over the elliptical part, so that the vessel will incline with the stern downwardly and the bow upwardly, and thereby enable it, through a reduction 90 of friction, in an obvious manner to obtain a higher speed.

When a vessel, having a hull with the herein-described features of construction, advances through the water, the bow cleaves the water with a minimum of resistance and disturbance, producing only relatively small waves to hamper the vessel in its progress. The provision in the forebody of a substantially flat bottom, where occurs the greatest 100 width of beam, enables the water to effect a wedging action for elevating the forebody without the production of a progress hampering waves, and tends at the same time to prevent rolling and pitching oscillations. 105 By means of the channels, the propeller and rudder are constantly supplied with a free and solid flow of water on which to act efficiently, in all kinds of weather and under all kinds of lading conditions. By locating 110 the propeller underneath the hull and by providing a substantially flat stern bottom, I moderate the wake as well as the stern waves. The specific contour and lines of 115 continuity of the hull, designed both to lessen frictional resistance and to concentrate the weights, and the relative arrangement of the bilges and keels combined in effect to make it more difficult for wave-impulses to 120 impart rolling oscillations to the vessel; and when the vessel does roll, these features tend 125 to produce a slow periodic time or period of natural roll.

From the foregoing it appears that the 130 construction is as follows: The forward underwater portion is V-shaped at the stem, joining the sides at the top parts of the V by bilges, which top parts gradually drop with the descending bilge 29 until the V-shaped portion becomes substantially flat 135

at line 7 (Fig. 1), where the bilges 29 merge into bilges 31, the latter being provided with keels 32. Just forward of the keels 32, the keel 23 starts and these keels form channels 33-34 which merge into a single channel 36 aft of the propeller and rudder, the channel being substantially flat at the stern.

Having thus described my invention, what I claim is:

- 10 1. The herein-described vessel-hull having in the forebody its greatest width of beam rising over a substantially flat bottom region, channels having commencement at said flat bottom region and extending aft and eventually uniting to discharge as a single channel at the stern.
- 20 2. The herein-described vessel-hull having in the forebody its greatest width of beam rising from a substantially flat bottom region, a keel having curvature to lie substantially flush with said flat bottom region and terminating aft of the longitudinal center, channels having commencement at said flat bottom region and extending along said keel 25 one channel on each side thereof, said channels merging at the termination of the keel

to form a single channel which discharges at the stern.

3. The herein-described vessel-hull having its greatest width of beam in the forebody 30 and from which the sides converge gently towards the stern, bilges and accompanying keels having commencement on the bottom below said greatest width of beam and extending aft along gently diverging lines, the 35 same ultimately running out at the gently converging sides of the afterbody.

4. The herein-described vessel-hull having a substantially flat bottom area under its forebody, a central keel extending to a point 40 aft of the longitudinal center, and a side keel on either side of the central keel extending from said flat bottom region to the stern, said side keels forming with the central keel two channels which merge into a single 45 channel at the termination of the central keel, said single channel extending to have free discharge at the stern.

Signed at New York, in the county of New York, and State of New York, this 50 18th day of December, A. D. 1925.

ROCHUS MAX zu LYNAR PASSY-de CHIMANG.
